E. H. WARD

FENCEPOST

Filed Nov. 27, 1925

UNITED STATES PATENT OFFICE.

ERNEST H. WARD, OF NEW CANTON, ILLINOIS, ASSIGNOR OF ONE-THIRD TO ROSCOE WALTHER, OF BARRY, ILLINOIS.

FENCEPOST.

Application filed November 27, 1925. Serial No. 71,753.

This invention relates to certain improvements in fence posts and has relation more particularly to a device of this kind especially designed and adapted for use in connection with wire fabric or the like, and it is an object of the invention to provide a post provided with means whereby slack occurring in the fence fabric or the like may be taken up with convenience and facility. 10 Another object of the invention is to provide a post of this kind with means whereby the fence fabric or the like may be readily stretched thereto or disconnected therefrom whereby the fabric or the like may be readily taken down or replaced in the event passage is desired for threshing machines and other farm machinery too wide for the ordinary gate.

The invention consists in the details of 20 construction and in the combination and arrangement of the several parts of my improved fence post whereby certain important advantages are attained and the device rendered simpler, less expensive and otherwise more convenient and advantageous for use, as will be hereinafter more fully set forth.

The novel features of my invention will 30 hereinafter be definitely claimed.

In order that my invention may be the better understood, I will now proceed to describe the same with reference to the accompanying drawings, wherein:—

Figure 1 is a view in elevation illustrating a fence post constructed in accordance with an embodiment of my invention;

Figure 2 is a view partly in elevation and partly in section of the structure as illustrated in Figure 1;

Figure 3 is a fragmentary view partly in cross section and partly in plan illustrating the means herein disclosed for holding a bar against rotation.

As disclosed in the accompanying drawings, P denotes the post proper which may be at a corner or in the middle of a fence section, the lower end portion of the post P being herein disclosed as set in a concrete foundation 1.

The post P adjacent to its upper end and to the foundation 1 is provided with outstanding and oppositely disposed arms 2 which may be integrally formed with the post P or may comprise separate casting disposed through the post as illustrated in the

accompanying drawings. The pair of arms 2 at each side of the post P provide vertically spaced bearings or mountings for a bar 3. The lower extremity of the bar 3 is received within a pocket or recess 4 provided in the upper surface of the lower arm 2 while the upper portion of said bar 3 is freely disposed through the upper arm 2 and terminates thereabove. The portion of the applied bar 3 above the upper arm 2 has disposed therethrough the angularly related openings 5 to provide means whereby a turning rod or kindred implement may be engaged with the bar when it is desired to rotate the same. The lower portion of the bar or that portion received within the pocket or recess 4 is provided therearound with circumferentially spaced openings 6 adapted to register with an opening 7 in the lower arm 2 in communication with the pocket or recess 4. A pin 8 or the like is adapted to be received within the opening 7 and a registering opening 6 to hold or lock the bar 3 against rotation in either direction.

As herein disclosed, the post P has co- 80 acting therewith the braces 9.

In practice, a clamp C of any desired type is operatively engaged with the wire fabric F and said clamp is operatively engaged with a bar 3 by the chains 10 or other flexible members. Upon rotation of the bar 3 said flexible members 10 will wind therearound resulting in sufficient pull being imposed upon the fabric F through the medium of the clamp C to take up substantially all 90 of the slack in the fabric. The fabric is then attached directly to the bar 3 by the clamp C' and upon continued rotation of the bar 3 the fabric is properly tightened, after which the bar 3 is held against retrograde rotation under the tension of the fabric by proper application of the pin 8.

During this operation of tightening the fabric F it will also be understood that the barbed wire W generally employed in connection therewith will also be properly tightened.

From the foregoing description it is thought to be obvious that a fence post constructed in accordance with my invention is particularly well adapted for use by reason of the convenience and facility with which it may be assembled and operated, and it will also be obvious that my invention is susceptible of some change and modi- 105 110

ification without departing from the principles and spirit thereof and for this reason I do not wish to be understood as limiting myself to the precise arrangement and formation of the several parts herein shown in carrying out my invention in practice except as hereinafter claimed.

I claim:—

10 In combination with a fence post and a wire fabric, a bar rotatably supported by the post to one side thereof and upon which the fabric is adapted to be wound, said bar being provided with means to rotate the

same, means for holding the bar against rotation, a clamp engageable with the fabric 15 at a point spaced from the bar, a flexible connection between said clamp and the bar, said flexible connection winding upon the bar to impose pull on the fabric upon rotation of the bar in one direction, and a second clamp 20 coacting with the bar for holding to the bar the fabric wound thereon.

In testimony whereof I hereunto affix my signature.

ERNEST H. WARD.
